FIG. 3.

Inventor:

George J. Blum

By Luther L. Miller,
Atty.

UNITED STATES PATENT OFFICE.

GEORGE J. BLUM, OF CHICAGO, ILLINOIS.

CHUCK.

1,090,096.

Specification of Letters Patent. Patented Mar. 10, 1914.

Application filed July 3, 1912. Serial No. 707,418.

To all whom it may concern:

Be it known that I, GEORGE J. BLUM, a citizen of the United States, residing at Chicago, in the county of Cook and State of Illinois, have invented certain new and useful Improvements in Chucks, of which the following is a specification.

Among the objects of this invention are to provide a vise, chuck or work-holder adapted to be used upon a variety of machine tools, as drill-presses, shapers, hacksaws, etc., to provide a work-holder having a great range of adjustment with regard to its position on the work table of the machine tool; to provide a work-holder, the movable jaw of which may be quickly moved toward and away from the fixed jaw; to provide a chuck construction consisting largely of castings and requiring a minimum of machine work; to produce a work-holder having large jaws in order that work of various dimensions may be securely clamped; to produce a work-holder of the class mentioned which shall be comparatively light; and in general to improve the efficiency and adaptability of this class of chuck.

The embodiment herein shown of the invention is substantially similar to that illustrated in my copending application Serial No. 467,341, filed December 14, 1908. Claims to said work-holder have been withdrawn from said copending application upon the requirement of the Patent Office, and hence the present application so far as certain features are concerned is to be considered as in the nature of a continuation of said application Serial No. 467,341, and issued as Patent No. 1,032,650, July 16, 1912.

In the accompanying drawings, Figure 1 is a plan view illustrating a portion of a work table and showing a work holder embodying the features of my invention secured to said table. Fig. 2 is a vertical sectional view taken in the plane of dotted line 2—2 of Fig. 1. Fig. 3 is a section on line 3—3 of Fig. 2. Fig. 4 is a perspective view of one element of the work-holder.

A denotes the work table of a drill-press or other machine tool. Such tables are ordinarily provided with a suitable number of grooves or slots *a* of T-shape in cross-section, only one groove being shown in the present drawings.

The work-holder comprises an elongated base 1 which may be secured to the table A by any suitable means, as, for ex-

ample, bolts 2, the heads of which lie within the undercut groove *a*, said bolts extending through notches 3 in the ends of the base 1, and being provided with nuts 4. Adjacent to one end of the base 1 is a fixed jaw 5 which may be of any preferred construction, but it is preferably cast integral with the base. Extending vertically through the base and transversely thereof, adjacent to the jaw 5, is a slot 6 adapted to receive a bolt 7. The lower side of the base 1 is recessed at 8 to receive the head of the bolt 7. This bolt may be used in securing jigs or the like to the work-holder. The bolt may also be used to secure the work-holder to the table A by placing the head of said bolt in the T-slot *a* and tightening up the nut 9. When it is desirable to secure the work-holder in a diagonal or angular position on the work table, the base 1 may be swung to the desired position and the nut 9 tightened to clamp the work-holder in place. It will be seen that the slot 6 permits of a wide latitude of rotational and lateral adjustment of the work holder with respect to the bolt 7. If, when the work-holder is placed diagonally of the work table, the bolt 7 is not sufficient to secure the work-holder in place, any suitable additional means may be employed, such as common clamps (not shown) engaging the work table and the side flanges 10 of the base 1.

A groove 11 of dovetail form in cross-section extends longitudinally of the base 1 from the jaw 5 to the opposite end of the base. The movable jaw 12 is provided with a foot 13 which has a dovetail guide 14 that is slidably mounted in the groove 11. In or upon the bottom of the groove 11 is formed a series of ratchet or inclined locking teeth 15 with which engages a tooth 16 on a block 17. Said block is slidable within a slot 18 formed in the foot 13, the lower portion 18^a of said slot being wider than the upper part. The block 17 is provided with lateral wings 19 lying within the portion 18^a of the slot 18. A spindle 20 extends through a tapped opening 21 in the block 17 and is arranged to bear at one end against the movable jaw 12. The opposite end of the spindle 20 is provided with a crank or handle 22. The lower side of the block 17 opposite to the tooth 16 is cut away as at 17^a in order to permit of tilting said block with relation to the base 1, to lift the tooth 16 away from the locking teeth 15. Assuming the spindle 20 to be out

of engagement with the jaw 12, the block 17 may be tilted to disengage the tooth 16 from the teeth 15 by raising the outer end of the spindle 20. The jaw 12 may then be slid freely toward and away from the relatively fixed jaw 5.

When a piece of work is to be secured in the work-holder, it is laid between the jaws 5 and 12, the movable jaw 12 is pushed up to the work, and the spindle 20 is rotated to press said movable jaw firmly against the work, the thrust being transmitted to the teeth 15 of the base 1 through the tooth 16.

By reference to Figs. 1 and 3, it will be seen that the edges of the jaws 5 and 12 at one side of the work-holder are alined or flush with one of the flanges 10. It will thus be seen that, if desired, the work-holder may be turned upon its side, the work-holder being secured in such position on the table A by means of an ordinary clamp (not shown) engaging the table A and the interior surface 1^a of the base 1. Said surface is provided by recessing the lower side of the base, such recessing also serving to lighten the construction. It will be seen that the work-holder may be quickly and firmly secured in any desired position upon any standard work table, and that the movable jaw 12 may be rapidly moved toward and away from the fixed jaw. The work-holder is very simple, consisting, as it does, of but four pieces, namely the base, the movable jaw, the block 17, and the screw-threaded spindle. The first mentioned three parts may be castings, and require no machine work except the formation of the tapped opening 21 in the block 16. By reason of their ample size the jaws 5 and 12 are adapted to hold large pieces.

When clamping a piece of work, the pressure upon the block 17 causes the wings 19 to press against the foot 13, whereby the guide 14 is pressed tightly against the undercut walls of the groove 11, thus positively preventing the jaw 12 from tilting or swinging out of alinement with the jaw 5. This feature is of especial value when a piece of work is clamped between the ends of the jaws or between the top or bottom portions of the jaws. The weight of the overhanging portion of the spindle 20 is sufficient to lift the guide 14 against the undercut walls of the groove 11, and any increase in such lifting or upward pressure, caused by the clamping of the work, augments the force with which the jaw 12 is held against tilting with reference to the jaw 5. This means for pressing the guide surfaces firmly together allows the guide portions to be formed with sufficient clearance between the surfaces so that they may be used without machining. The clearance allows the rough surfaces to pass freely, while the tilting brings the surfaces firmly together when the

holder is in use; and the roughness of the surfaces increases the rigidity of the jaws.

The embodiment herein shown is susceptible of modification, within the scope of the appended claims, hence the invention is not limited to the details set forth.

I claim as my invention:

1. A work-holder comprising a base having a fixed jaw, said base having an undercut groove therein, locking teeth in said groove, a movable jaw having a foot slidable upon said base, said foot being provided with a guide fitting in said undercut groove, said foot having an undercut slot therein, a member movable with relation to said movable jaw and having a guide co-operating with said slot, said member adapted to engage said locking teeth, and means carried by said member for moving said movable jaw.

2. A work-holder comprising a base having a fixed jaw, said base having an undercut groove therein, the upper surfaces of said groove being beveled, locking teeth in said groove, a movable jaw having a foot slidable upon said base, said foot being provided with a guide fitting in said undercut groove and having beveled surfaces adjacent the beveled surfaces of said groove, said foot having an undercut slot therein parallel with said groove, a member movable with relation to said movable jaw and having a guide co-operating with said slot, said member adapted to engage said locking teeth, and means carried by said member for moving said movable jaw.

3. A work-holder comprising a base carrying a fixed jaw, said base having an undercut groove therein, a movable jaw having a foot slidable upon the base, said foot being slotted and being provided with a guide fitting in said undercut groove, a member slidably mounted in said slot and adapted to engage said locking teeth and being tiltable out of engagement with said teeth, and means carried by said member for moving said movable jaw.

4. A work-holder comprising a base having a fixed jaw, said base having an undercut groove therein, locking teeth in said groove, a movable jaw having a foot slidable upon said base, said foot being provided with a guide fitting in said undercut groove, said foot having an undercut slot therein, a member movable with relation to said movable jaw and having a guide co-operating with said slot, said member adapted to engage said locking teeth, and means carried by said member for pressing said jaws together and tending to tilt said member.

5. A work-holder comprising a base having a fixed jaw, said base having an undercut groove therein, locking teeth in said groove, a movable jaw having a foot slidable upon said base, said foot being pro-

vided with a guide fitting in said undercut groove, the upper adjacent surfaces of said base and said guide being beveled, said foot having an undercut slot therein, a member 5 movable with relation to said movable jaw and coöperating with said slot, said member adapted to engage said locking teeth, and means carried by said member for pressing said jaws together and for tilting said 10 member.

6. A work-holder comprising an elongated base adapted at its ends for attachment to a work table, said base having a fixed jaw adjacent to one end thereof, and having an 15 undercut groove extending from said jaw to the opposite end of said base in the upper side of the base, a movable jaw having a foot adapted to slide upon the upper surface of the base, said foot having on its under side a 20 guide adapted to fit within said undercut groove, said foot having an undercut slot therein, locking teeth upon the bottom of the undercut groove of the base, a member having a tooth adapted to engage said locking 25 teeth, said member extending through the slot in the foot, and having lateral projections lying within the undercut portions of the slot in said foot, said member being adapted to tilt on said projections to carry 30 its tooth into and out of engagement with said locking means, and a screw-threaded spindle extending through said member and bearing against said movable jaw.

7. A work-holder comprising a base having a fixed jaw, guide means on said base, a movable jaw having guide means coöperating with the other guide means, a substantial clearance being provided normally between said guide means, and means to press the second mentioned guide means against the said other guide means to assist in holding the movable jaw rigid.

8. A work-holder comprising a base having a fixed jaw, guide means on said base, a movable jaw having other guide means with slanting surfaces thereon coöperating with the first mentioned guide means, locking teeth on said base, a member having a tooth to engage said locking teeth, means on said 50 member bearing against the second mentioned guide means to press said guide means against the first mentioned guide means, and means carried by said member and bearing against said movable jaw for moving the latter toward the fixed jaw and for pressing said guide means together.

9. A work-holder comprising an elongated base, a fixed jaw near one end of said base, said base having guide means with a slanting surface extending longitudinally thereof, 60 a movable jaw having guide means with a slanting surface slidable along the slanting surface of said other guide means, a member arranged to engage said base and arranged to tilt and to press said two slanting 65 surfaces together, and a screw-threaded spindle adapted to bear against said movable jaw, said spindle extending substantially longitudinally of the base and tending to tilt said member. 70

10. A work-holder comprising an elongated base, said base having a fixed jaw adjacent to one end thereof, a movable jaw having a foot, said foot having sliding connection with said base, said foot having an undercut slot therein, locking teeth on said base, a member having a tooth adapted to engage said locking teeth, said member extending through the slot in the foot and having lateral projections lying within the undercut portions of the slot in said foot, said member being adapted to tilt on said projections to carry its tooth into and out of engagement with said locking means, and a screw-threaded spindle extending through 85 said member and bearing against said movable jaw. 80

11. A work-holder comprising a base having a fixed jaw, guide means with slanting surfaces on said base, a movable jaw having 90 guide means with slanting surfaces coöperating with the other guide means, and means to press the slanting surfaces of the second mentioned guide means against the slanting surfaces of said other guide means to assist 95 in holding the movable jaw rigid.

12. A work-holder comprising a base having a fixed jaw, said base having an undercut groove therein, locking teeth in said groove, a movable jaw having a foot slidable 100 upon said base, said foot being provided with a guide fitting in said under-cut groove; a member movable with relation to said movable jaw, and adapted to engage said locking teeth, and means carried by said member for 105 moving said movable jaw.

In testimony whereof I hereunto affix my signature in the presence of two witnesses.
